UNITED STATES PATENT OFFICE.

JOSEPH A. NICKELSON AND JOHN FREDRIKSON, OF NEW YORK, N. Y., ASSIGNEES TO
SAID NICKELSON.

VAPORIZER.

1,227,649.

Specification of Letters Patent.

Patented May 29, 1917.

Application filed May 6, 1916. Serial No. 95,846.

To all whom it may concern:

Be it known that we, JOSEPH A. NICKELSON and JOHN FREDRIKSON, citizens of the United States, and residents of the borough 5 of Bronx, city and State of New York, have invented certain new and useful Improvements in Vaporizers, of which the following is a specification accompanied by drawings.

This invention relates to vaporizers for 10 vaporizing heavy liquid hydrocarbon fuels, such as kerosene, for combustion engines, and the objects of the invention are to enable a cheap and simple apparatus to be connected with the exhaust pipe of the engine, without 15 complicated parts to get out of order. Another object is to produce a vaporizer which will permit a free flow of the gases and will not burn out under high temperatures.

20 To these ends the preferred form of the invention is shown in the accompanying drawings, in which—

Figure 1 is a side elevation of a combustion engine having a vaporizer embodying 25 the invention;

Fig. 2 is an end view of the apparatus with part of the engine to the center line removed;

Fig. 3 is an enlarged longitudinal sectional elevation through the vaporizing chamber on line 3—3 of Fig. 4 with part of the exhaust pipe broken away; and

Fig. 4 is a horizontal sectional view of Fig. 3 on line 4—4.

35 Referring to the drawings, A represents a combustion engine, having the usual carbureter B of any suitable type, connected by pipe C to the vaporizing chamber D, preferably located in the exhaust pipe E of the engine. The vaporizing chamber D also communicates with the engine cylinders by means of the intake pipes or manifold F.

The vaporizing chamber is formed by 45 means of headers G and H suitably provided in the sides of the exhaust pipe E, in this instance the headers being formed in one piece with the exhaust pipe, although other methods of construction may be employed.

Vaporizing tubes J are set into the headers G and H in any suitable manner, and these tubes should preferably be made of brass or other suitable metal, which will withstand high heat for considerable periods of time without deterioration. We have

found brass to be the best material so far known to us for the vaporizing tubes.

Over the header G is placed a cap K, preferably bell-shaped, and connected to the pipe C, while a similar shaped cap L is placed over the header H and connected to the engine manifold F. It will be observed by reference to Figs. 3 and 4 that the caps K and L form enlarged chambers over the ends of the vaporizing tubes, so that the entrance and exit of the gases to and from the vaporizing tubes is substantially free and unobstructed. This is a feature of material importance.

Furthermore, the fact that the gases pass through and not over the vaporizing tubes 70 is of great practical importance, because in this way more perfect vaporization is secured, owing to the free mixing passages for the gases. The gases will pass more freely through the tubes than over them, and the 75 design of the apparatus is to provide a free and unobstructed passage directly through the tubes.

Both the exhaust pipe E and vaporizing chamber D are preferably water jacketed by 80 means of the jacket P, in order to enable the temperature of the vaporizing chamber to be controlled within desirable limits, as otherwise its temperature has been found to increase to a degree beyond that required for 85 proper vaporizing.

We claim and desire to obtain by Letters Patent the following:

1. A vaporizer for heavy liquid hydrocarbon fuels, comprising in combination with a 90 combustion engine and its horizontal exhaust pipe, of upper and lower cylindrical headers in the top and bottom of said exhaust pipe, forming a cylindrical vaporizing chamber, vaporizing tubes inserted vertically in said 95 headers and lying within the vaporizing chamber, upper and lower bell-shaped caps over each of said headers, a fuel conduit communicating centrally with the lower one of said bell-shaped caps and leading to the 100 carburetor of the engine, and the intake pipe or pipes of the engine communicating centrally with the upper one of said bell-shaped caps, whereby the fuel to be vaporized passes freely through the heated vaporizing tubes, 105 and the hot exhaust gases pass around the tubes, and a water jacket surrounding both the exhaust pipe and the sides of the said

- cylindrical vaporizer chamber, to prevent the temperature of the vaporizing chamber from increasing beyond a predetermined degré.
5. 2. A vaporizer for heavy liquid hydrocarbon fuels, comprising in combination with a combustion engine and its exhaust pipe, of a vaporizing chamber formed in said exhaust pipe and having walls extending at substantially right angles outwardly from the walls of said pipe, headers covering the outer ends of said vaporizing chamber, vaporizing tubes inserted in said headers and lying within the vaporizing chamber, caps over each of said headers, a fuel conduit communicating with one of said caps and leading to the carbureter of the engine, and the other cap communicating with the engine manifold, whereby the fuel to be vaporized passes through the
- heated vaporizing tubes and the hot exhaust 20 gases pass around the tubes, and an outer wall forming a water jacket around the exhaust pipe, said wall also being extended outwardly at an angle adjacent the walls of the vaporizing chamber to form a water 25 jacket partially surrounding the said vaporizing chamber, to cool the exhaust gases and prevent the temperature of the vaporizing chamber from increasing beyond a predetermined limit. 30

In testimony whereof we have signed this specification in the presence of two subscribing witnesses.

JOSEPH A. NICKELSON.
JOHN FREDRIKSON.
